HOLDER FOR FOOD BOWLS FOR PETS

Tony Robert, 5701 Southwest Freeway,
Houston, Tex. 77027

Filed Apr. 19, 1967, Ser. No. 6,754

Term of patent 14 years

(Cl. D30—13)

FIGURE 1 is a top perspective view showing one end and a side of the holder for food bowls for pets, showing my new design;

I claim:

The ornamental design for a holder for food bowls for pets, as shown.
